UNITED STATES PATENT OFFICE

JOHN AUGUST LUND, OF BATAVIA, ILLINOIS, ASSIGNOR TO CHALLENGE COMPANY,
OF BATAVIA, ILLINOIS, A CORPORATION OF ILLINOIS

LUBRICATING SYSTEM

Application filed October 18, 1926. Serial No. 142,327.

This invention relates to pump jacks and more particularly to lubricating systems therefor, although certain features thereof may be employed with equal advantage for other purposes.

It contemplates more especially the provision of means for automatically lubricating the coating elements simultaneously with the movement thereof, thereby insuring 10 against excessive wear between the relatively moving parts.

One object of the present invention is to provide novel means for insuring the lubrication at all times of coating elements 15 simultaneously with the movement thereof.

Another object is the provision of inexpensive and improved lubricant conveying means.

A further object is to provide lubricating 20 instrumentalities which are inexpensive, uncomplicated and positive in their function.

Other objects and advantages will appear from the following description of an illustrated embodiment of the present invention.

In the drawings:

Figure 1 is a view in elevation of a machine embodying features of the present invention.

Figure 2 is a sectional view taken substantially along line II-II of Figure 1.

Figure 3 is a sectional view in elevation taken substantially along line III-III of Figure 2.

Figure 4 is a fragmentary detail view 35 taken substantially along line IV-IV of Figure 1.

Figure 5 is a sectional view taken substantially along line V-V of Figure 2.

Figure 6 is a sectional view taken substantially along line VI-VI of Figure 4.

Figure 7 is a sectional view taken substantially along line VII-VII of Figure 3.

Figure 8 is a sectional view taken substantially along line VIII-VIII of Figure 3.

Figure 9 is a fragmentary sectional view 45 taken substantially along line IX-IX of Figure 2.

The lubricating means selected for illustration is shown in connection with a pump jack comprising, in this instance, a casing

10 suitably formed to carry a lubricant therein. Within the casing 10 there is provided a standard or web 11 formed integral therewith and having the upper surface thereof provided with upstanding flanges 12 which 55 define a drip trough 13 disposed above the surface of the lubricant within the casing. The standard 11 is bored to define a vertical passage 14 therethrough to receive a pump rod 15 reciprocable therein and through an extension 16 disposed below the casing and 60 formed integral therewith. The periphery of the bore 14 is provided with an upwardly extending peripheral projection 17 so as to prevent the leakage of the lubricant contained in the drip trough 13 through the pump rod bore 14 (Figure 9). A pair of 65 guide rods 18 and 19 are equally spaced from the pump rod 15, they being fixed to the standard 11 within the trough 13 in any 70 suitable manner, in this instance, by providing threaded engagement therebetween. The upper extremities of the rods 18 and 19 are maintained in spaced relation by means of a bracket 20 suitably bored as at 21 and 75 22 to receive the extremities of the guide rods 18 and 19, respectively, which are held therein by the set screws 23 and 24 of standard type. The pump rod 15 is reciprocally guided within the bore 14 of the casing 10 80 by means of a guide roller 25 a well known equivalent for a cross head, and which is journaled on a horizontally disposed shaft 26 fixed to a saddle 27 having a bifurcated portion straddling the rod 19 and detachably secured to the extremity of the pump rod 15 by threaded engagement therewith. 85 To guide the pump rod 15 vertically, the roller 25 is provided with a peripheral groove 28 to receive the vertical guides 18 and 19 therein, it having frictional contact with one or the other of said guides to effect rotation of the roller 25 responsive to reciprocation of the pump rod 15.

Reciprocation is imparted to the pump rod 95 15 by means of suitable cranks formed by the gears 33-33 and connecting rods 29-29, in this instance, operatively connected to the roller shaft 26 thru the hubs 30 formed integral with the extremities of connecting 100 rods.

rods 29. The other extremities of said rods 29 are also provided with suitable hubs 31 having projecting studs 32 associated therewith, and, in this instance, projecting through suitable apertures provided in the 5 pair of spaced spur gears 33, thus providing cranks. The gears are journalled on a shaft 34 centrally supported in the standard or web 11. The gears 33 are maintained in 10 spaced relation on the shaft 34 by means of a clip 35 fixed to the standard 11 by the threaded stud 36 in a manner more fully illustrated and described in my copending application of even filing date herewith, Serial No. 15 142,326, and now issued in Patent No. 1,627,- 708. It will thus be apparent that rotation of the gears 33 will impart reciprocation to the pump rod 15 which is vertically guided by means of the roller 25 having slight frictional contact with the guide rods 18 and 19.

20 Rotation is imparted to the gears 33 by means of a drive shaft 37 connected exteriorly of the casing 10 to any suitable source of power. The shaft 37 is enclosed in a shaft 25 housing 38 formed integral with the casing 10 on one side thereof, the shaft being journalled in suitable bearings 39 and 40 of standard construction, positioned in suitable bearing raceways 41 and 42 provided in the 30 shaft housing 38 and the standard 11, respectively. The portion of the shaft 37 which is within the casing 10 is provided with a pair of pinions 43—43 spaced thereon to mesh with the spur gears 33—33 hereinabove described. The casing 10 is provided with a suitable threaded aperture 44 coaxial with the shaft 37 to receive a detachable plug 45 to permit the pinions 43—43 to be readily removed therefrom. The extremity of the 40 shaft 37 projecting exteriorly of the shaft housing 38 is, in this instance, provided with suitable hubs 46 and 47 to receive the vanes of a windmill wind wheel constituting the source of power in the present embodiment.

45 The fact that the coating movable elements are subjected to comparatively high speeds and stress reactions makes it imperative or at least highly desirable that lubricating means be provided for decreasing the friction and wear between the coating parts to a minimum. Numerous types of forced lubrication systems have heretofore been proposed, but have not proven entirely satisfactory due to their complex construction and 50 their unnecessary consumption of power. The means employed, in this instance, are designed to overcome the difficulties heretofore experienced, and comprises, in this instance, means to elevate the lubricant along 55 the guide rods 18 and 19 to maintain the lubricant film on the shaft 26, upon which the grooved guide wheel 25 is mounted. The elevating means in this instance comprises an oil dipper device 48 which envelops the 60 guide rod 19 and is loosely secured at one

extremity thereof to the saddle 27 which imparts reciprocation thereto. The spiral oil conveyor 48 surrounds one or both of the rods 18 and/or 19 and has lost motion connection with the saddle 27 (see Fig. 1). 70 In the present embodiment this oil dipper mechanism 48 consists of a wire loosely coiled about one of the vertical guide rods 19. The upper end of the wire passes loosely through a part of the saddle 27 and has a turned out end 48' and a kink 48''. The stroke of the conveyor 48 is never as great as the stroke of the power rod so that when the stroke of the latter is changed, the extent of movement of the dipper is unaltered. The dipper 48 enters the drip trough 13 containing lubricant, and on the up stroke carries with it the lubricant between the convolutions of the spring. This wiping action tends to cover the rod 19 with a film of lubricant adapted to eventually find its way to the peripheral groove 28 of the roller 25 which contacts therewith. The roller 25 is provided in this instance with a plurality of radial grooves 49 which effect 80 communication between the peripheral groove 28 of the roller and the axis thereof, whereby the lubricant is transferred or conveyed to the surface of the shaft 26 upon which the roller 25 is journalled. As stated above, the trough 13 is disposed above the level of the lubricant so that the former must be supplied with the lubricant from the casing 10. The means for accomplishing this end, in this instance, consists of an inwardly 90 extending corrugated member 50 (Figures 2 and 5) secured to one of the gears 33 as by fasteners 51, near the periphery thereof, so as to dip in the lubricant contained in the chamber with the rotation thereof to periodically transfer or splash lubricant from the casing 10 to the drip trough 13, thereby maintaining a supply of lubricant therein.

To effectively lubricate the shaft bearings 39 and 40 the lubricant is caused to travel 110 along the shaft 37 as will subsequently appear. To accomplish this end in the present embodiment, an additional drip trough 52 is provided as an extension of the trough 13 to convey the overflow lubricant from 115 the trough 13 to a position above the shaft 37. The trough 52 as will appear from the showing, is somewhat shallower and disposed below the upper surface of the flanges 12 defining the trough 13 so that the overflow therefrom will be directed to the trough 52 which has a discharge orifice 53 immediately above the shaft 37. Disposed below the discharge orifice 53 of the trough 52 is a deflector 54 (Figures 3 and 8) comprising 120 an annular flange which is slotted as at 55 to define an inclined surface 56 to deflect the lubricant dripping thereon, axially of the shaft 37. The lubricant is conveyed along 125 the shaft by novel conveying means com- 130

prising, in this instance, a helical spring 57 having the convolutions thereof embracing the shaft and disposed between the bearing 41 and the deflecting means 55. The spring 57 is preferably held stationary with respect to the shaft 37 in any appropriate manner so that the lubricant deflected thereto will be conveyed between the convolutions of the spring 57 defining a helical path which causes axial conveyance of the lubricant responsive to the rotation of the shaft 37 to properly lubricate the coacting elements disposed in the path thereof. It is obvious that similar means may be provided on the shaft 37 between the pinions 43 to effect the proper distribution of lubricant to the bearing 40. It is to be noted that apertures 58 may be provided in the trough 13 to lubricate the bearing 40 and other coacting parts in the vicinity thereof. It is to be noted that the shaft housing 38 is provided with a runway 59 inclined downwardly toward the casing 10 to effect the return of the lubricant conveyed along the shaft 37, which drops downwardly at the terminal end of the shaft housing so that the lubricant may be repeatedly used.

I am aware that many changes may be made, and numerous details of construction may be varied through a wide range without departing from the principles of this invention, and I therefore do not purpose limiting the patent granted hereon, otherwise than necessitated by the prior art.

55 I claim as my invention:

1. The combination with a casing having a lubricant therein, of a trough disposed in said casing above said lubricant, means in said casing for periodically transferring lubricant from said casing to said trough, a rod fixed on said trough, means for elevating lubricant along said rod, said elevating means comprising a reciprocable member coacting with said rod, and a conveyor fixed to the member and enveloping said rod.

2. The combination with a casing having a lubricant therein, of a trough disposed in said casing above said lubricant, means in said casing for periodically transferring lubricant from said casing to said trough, a rod fixed on said trough, means for elevating lubricant along said rod, said elevating means comprising a reciprocable member coacting with said rod, a conveyor fixed to the member and enveloping said rod, and a guide wheel rotatable on said rod responsive to the reciprocation of said reciprocable member.

3. The combination with a casing having a lubricant therein, of a trough disposed in said casing above said lubricant, means in said casing for periodically transferring lubricant from said casing to said trough, a rod fixed on said trough, means for elevating lubricant along said rod, said elevating

means comprising a reciprocable member coacting with said rod, a conveyor fixed to the member and enveloping said rod, and a guide wheel rotatable on said rod responsive to the reciprocation of said reciprocable member, there being radial grooves in said wheel to transfer the lubricant from said rod to the axial bore of said wheel.

4. The combination with a casing having a lubricant therein, of a trough disposed in said casing above said lubricant, means in said casing to transfer lubricant from said casing to said trough, lubricant conveying means disposed beneath said trough, said conveying means comprising a driving shaft, a helical stationary member enveloping said shaft, and means on said shaft for deflecting the drip from said trough to said conveyor, said deflecting means comprising a shoulder having irregular means on the surface thereof.

5. The combination with lubricant drip supply means, of a rotatable shaft disposed below said means, means on said shaft for deflecting dripping lubricant axially of said shaft, and means for carrying said deflected lubricant along the surface of said shaft, said deflecting means including an annular shoulder, having grooves therein to define an inclined deflecting surface.

6. In combination, a container having lubricant therein, a plurality of fixed upright rods associated with said container, a movable member, a lubricant conveyor loosely disposed about one of said rods and having one of its ends resiliently attached to said movable member, a reciprocating rod secured to said member, and means for reciprocating said rod for actuating said conveyor into and out of said container for elevating lubricant along one of said fixed rods.

7. In combination, a container having lubricant therein, a trough disposed in said container above said lubricant, rotatable means for transferring lubricant from said container into said trough, a plurality of fixed rods in said trough, a reciprocal rod having a lateral extending member disposed adjacent one of said fixed rods, a lubricant conveyor loosely disposed about said last-mentioned fixed rod and having its upper end resiliently attached to said member, and means for reciprocating said conveyor into and out of said trough for elevating lubricant along one of said fixed rods.

In testimony whereof I have hereunto subscribed my name.

JOHN AUGUST LUND.
